United States Patent Office

Des. 198,447
Patented June 16, 1964

198,447

MOLDING

Pontus Gunnar Lovgren, 6537 Homewood Ave.,
Los Angeles, Calif.

Filed Nov. 19, 1963, Ser. No. 77,492

Term of patent 14 years

(Cl. D13—6)

FIGURE 1 is a perspective view showing the inventive molding, and presenting the end aspect and top aspect thereof in perspective.

FIGURE 2 shows an end view of the molding.

I claim:

The ornamental design for a molding substantially as shown and described.
